UNITED STATES PATENT OFFICE.

JAMES M. BUTCHER, OF CHICAGO, ILLINOIS.

ALARM MECHANISM.

Application filed September 30, 1922. Serial No. 591,452.

To all whom it may concern:

Be it known that I, JAMES M. BUTCHER, a citizen of the United States, and a resident of Chicago, in the county of Cook and State of Illinois, have invented certain new and useful Improvements in Alarm Mechanism, of which the following is a description, reference being had to the accompanying drawings, which form a part of my specification.

My invention relates to an alarm mechanism more especially adapted for use in connection with a jewel or cash box or container for valuable documents and has for its object the provision of mechanism which will be positive in its operation and of such simple and sensitive construction that any unauthorized handling or movement of the box or container will result in the actuation of the alarm mechanism when the latter has been "set."

My invention contemplates the provision of mechanism which may be set by the owner of the box or container before the lid or top has been closed and locked in place; the alarm mechanism involving separate alarm sounding elements which may be separately employed; both of which, however, are adapted to be set into operation through the same gravity controlled means.

The objects and operation of my improved mechanism will be more readily comprehended from the detailed description of the accompanying drawings, wherein:—

Figure 1 is a sectional view taken through one end of a suitable box or container provided with my improved mechanism, a portion whereof is broken away and shown in section.

Figure 2 is a sectional plan view taken substantially on the line 2—2 of Figure 1.

Figure 3 is a vertical sectional view taken on the line 3—3 of Figure 1 looking in the direction of the arrows.

Figure 4 is a detail view in perspective of a guide and supporting member for the tripping elements of the mechanism.

Figure 5 is an enlarged sectional view taken on the offset line 5—5 of Figure 1 looking in the direction of the arrows.

Figure 6 is a rear elevation of the mechanism with portions broken away and shown in section.

Figure 7 is a detail sectional view taken on the line 7—7 of Figure 5 looking in the direction of the arrows.

Figure 8 is a detail view in perspective of an auxiliary alarm sounding element.

Figure 9 is a detail view in perspective of the upper end of the gravity-controlled trip element.

The invention as disclosed in the drawings is especially adapted for use in connection with a suitable box or container, namely of the type usually employed as a cash or jewel box, shown at 15, and provided with a suitable hinged top or lid 16, to permit access to the box interior; my improved alarm mechanism being preferably secured to one of the end walls of the box on the interior thereof, with certain of the mechanism enclosed in a suitable housing or shell as indicated at 17 in order that the contents of the box cannot come into contact with the tripping element whereby the alarm is set off.

The mechanism comprises a suitable bell, indicated at 18, provided with the usual spring driven mechanism controlled by a suitable pawl or detent; the spring in the construction shown being controlled or wound through proper rotation of the bell or gong whereby the arbor to which the spring, indicated at 19, is secured. The alarm mechanism just referred to is of a well known construction, provided with a striker 20 actuated by the star-wheel 21 secured on an arbor provided with a pinion 21^a meshing with a pinion 22 whose arbor is provided with a small pinion 23 which meshes with the pinion 24 secured on the arbor on which spring 19 is wound. By inserting the pinions 22 and 23 for driving star-wheel 21 which actuates striker 20, it is apparent that I am enabled to secure a longer duration of alarm when the mechanism is set in operation than would be the case where pinion 24 is placed in direct operative relation with the pinion mounted on the arbor containing star-wheel 21. Mounted in the rigidly held walls or member 25 and 26 of the alarm mechanism just described is a slidably mounted plunger 27, maintained in normal position, namely so as to protrude a predetermined extent through wall 26, by means of a suitable spring as at 28 and this plunger is provided with a collar or shoulder as at 29 which normally engages the upper end of the detent 30 so as to hold the lower end thereof in immovable relation with the star-wheel 21 and thus prevent unwinding action of the various pinions induced by the tension

105

110

of spring 19. The plunger 27 normally protrudes through wall 26 and is disposed into the path of a lever 31 pivotally mounted at 32 between the wall 26 and the main 5 wall 33 of the alarm mechanism.

The lower end of the lever 31 is preferably given a twist or bent at a slight inclination as at 34 so as to permit sliding engagement with the end of plunger 27 when the 10 lever 31 is oscillated about its pivotal point through the action of a spring 35 which normally tends to force the inwardly twisted or bent portion 34 of the lever into pressing engagement with the end of plunger 27; one 15 end of the spring 35 having operative engagement with lever 31, while the other end is suitably secured to the wall 33.

The upper end of lever 31 is shown slightly offset and disposed through a slot 20 in the shell or tubular portion 36 which is immovably mounted in the portions 37 of the main wall 33. The shell or tubular portion 36 is provided with a plunger 38 with which the end of lever 31 has ball-and-socket 25 connection as at 39, whereby plunger 38 will be forced to move downwardly by the action of lever 31 induced by the spring 35. The upper end of plunger 38 is shown provided with a finger control latch member 40 preferably loosely mounted on plunger 38 to permit latch member 40 to be swung laterally onto the upper end of tubular shell or portion 36, thereby holding the plunger upward, against the downward pull of lever 31, out of 30 operative position. The tubular shell or portion 36 at its upper end is provided with a slot as at 41 into which the latch member 40 may pass when oscillated slightly forward of the position shown in Figure 6, 35 thereby permitting the plunger 38 to move into "set" position. The lower end 42 of the plunger 38 is preferably yieldingly connected to the upper portion of the plunger 38 by a link connection as at 43, to allow lateral or slight sidewise movement of the portion 42 as the plunger moves completely 40 downward after same is released by mechanism hereinafter described. The portion 42 is shown slightly reduced intermediate of its 45 ends, that is to say the sides are shown concaved, see Figure 3, to permit a slight lateral play at the lower end of the tubular portion or shell 36. The lower portion 42 of the plunger 38 is shown provided with a tapered 50 or needle point at 44 which is adapted to rest on a tapered or needle portion 45 of a gravity controlled pendant or weight member 46. The gravity controlled member 46 is preferably shown provided with a threaded aperture 55 to receive the threaded stem 47 of the needle member 45, although it may be made integral therewith if desired. The needle member 45 is shown mounted in a yoke 48, with the lower or blunt end of the needle 60 protruding slightly into the yoke 48, where

it is rounded and rests in a small depression or socket 49 formed in the bracket member 50, whose upper end is shown in the nature of a collar portion 51 adapted to be removably secured to the lower end of the shell or 70 tubular portion 36 by means of a set-screw as at 52.

From the construction shown it is apparent that the gravity actuated pendant or member 46 is rather delicately supported in 75 the socket 49, with the major part or weight beneath its support, which allows it to readily swing upon any slight movement or jar being given to the box or container in which the mechanism is mounted; and by reason of the fine contact between the needle points 44 and 45, any minute movement of the gravity controlled member or pendant 46 out of vertical position, and therefore out of supporting position for the 80 lower end of plunger 38, will permit plunger 38 to move downwardly; while the loose joint or connection between the main portion of the plunger 38 and its lower portion permits the lower portion 42 to move to one 85 side of its vertical axis and therefore out of alignment with the needle point 45 to enable the plunger to complete its downward travel. This downward movement of the plunger, through the action of the spring 35, will 90 cause the lower end 34 of lever 31 to press plunger 27 inwardly, thereby moving its collar or shoulder 29 out of engagement with the detent 30 and permitting the main spring 19 to cause rotation of the various 95 pinions and the star-wheel 21 which will give the striker 20 the necessary vibration for 100 ringing the bell or gong 18.

As an auxiliary alarm mechanism I provide means for discharging a cartridge which 105 is intended to be placed in the barrel or holder 53 disposed adjacent an opening in the wall of the box or container 15. The cartridge is discharged by a trigger or plunger member 54 shown provided with 110 the tapered cartridge engaging point 55. The main wall of the alarm-holding housing or shell 33 is shown provided with right angularly disposed portions 56, 56 apertured to permit sliding movement of the trigger or plunger 54. The plunger 54 is under constant spring pressure through the action of a spring 57 shown disposed about the trigger or plunger 54 and bearing against one of the wall portions 56, while the other end 115 engages with the finger engaging portion 58 shown formed integral with the trigger or plunger 54. I provide a breech-member 59 which is pivoted at 60 intermediate of the lug or wall portion 56 and the barrel or cartridge holder 53 so as to permit the member 59 to be swung upwardly and out of juxtaposition with the barrel or cartridge holder 53 when the plunger or trigger member 54 has been retracted. The end of the member 120

59, adjacent to the cartridge holder 53, is apertured for centering the point 55 of the plunger or trigger 54 and this end of the member 59 is in close proximity to the cartridge-holder 53 to prevent back flash or firing of the cartridge.

The trigger or plunger member 54 on its lower side is provided at a suitable point with a notch as at 61 adapted to engage with the 10 lug or wall portion 56 when the trigger has been retracted against spring 57; which latter, by reason of being disposed about the trigger or plunger 54, causes the plunger or trigger 54 to drop down at the rear or inward end thereof when the same has been drawn back sufficiently, thus causing the plunger or trigger to be held in "cocked" or "set" position.

The release of the trigger or plunger 54 20 from its "cocked" or "set" position is induced by a loosely mounted lever 62, the upper end whereof is formed to engage with the lower side of the trigger or plunger 54 when the latter has been retracted or placed in 25 "cocked" condition; while the lower end of the lever 62 extends rearward of the gong holding shell 26 to a point in proximity to an arbor 63 which is adapted to rotate with the master pinion 24, namely with the arbor 30 on which the main spring 19 is wound. This arbor 63 is provided with a pawl 64 loosely mounted thereon so as to be free to drop into the depending or vertical position shown in Figure 6 when it has passed the point 35 where it will engage with the lower end of the lever 62. The arbor 63 is shown bent at right angles to its axis and the immediate end turned inward and into the path of pawl 64 in order that the inturned end, 40 shown at 65, will engage with the pawl 64 after the arbor has been partially rotated, thereby lifting the pawl 64 from the normal position shown in full lines in Figure 6 into the position indicated in dotted lines, where it will engage with the lower end of lever 45 62 which assumes the position indicated in dotted lines in said figure through the inward movement of the plunger or trigger 54, namely a position where the upper end of lever 62 will be in engagement with the lower side of plunger or trigger 54. The continued rotation of arbor 63 will force pawl 64 against the raised lower end of lever 62, causing said lever to be moved 50 about its pivotal point, thereby forcing trigger or plunger 54 upwardly sufficient to move notch 61 of the plunger out of engagement with the lug or wall portion 56, thus releasing the plunger and permitting the 55 spring 57 to become distended. The spring will cause the plunger to be suddenly forced forward, bringing its point 55 into forcible or striking engagement with the cartridge and causing the latter to be discharged. By 60 mounting the breech 59 pivotally as de-

scribed, it is evident that the shell or discharged cartridge may be easily removed by withdrawing plunger or trigger 54 sufficiently to move its point 55 out of the aperture in the breech which permits member 59 70 to be swung upwardly away from the barrel 53 and while member 59 is in this position the barrel or holder 53 may be provided with a new cartridge.

By loosely mounting the pawl 64 as shown 75 and described, it is apparent that the pawl will drop to the normal position shown in full lines as soon as it has passed out of engagement with the lower end of lever 62, so that the pawl 64 will not remain at a point 80 where it would interfere with the re-setting of the cartridge discharging mechanism.

To place the mechanism in alarm sounding condition, it is, of course, essential to see that spring 19 of the bell or gong is sufficiently wound and after the box or container has been placed where it is to remain, namely at rest in horizontal position where the gravity member 46 will be disposed in vertical position, the plunger 38 is then slightly lowered by grasping finger control latch member 40 and turning the same so as to register with the slot 41, which will permit the plunger 38 to move slightly downward through the action of the pressure 85 exerted thereon by lever 31 induced by its spring 35. Such lowering of the plunger 38 will bring its lower point 44 at rest on the needle point 45 of gravity member 46, as sidewise movement of the portion 42 is impossible while wholly within the shell or tubular portion 36. In view of the fine or minute holding relation provided between the needle points 44 and 45, it is apparent that the slightest movement or jar of the 90 box or container will cause the gravity member 46 to oscillate out of vertical position, thereby moving its point 45 out of holding relation with the point 44 and permitting plunger 38 to move further downward. This will permit lever 31 to oscillate through the action of its spring 35 and cause the lower end 34 of the lever 31 to pass across the protruding end of plunger 27, 95 forcing the plunger or rod against the action of the spring 28 and moving the collar or lug 29 on the plunger 27 out of holding engagement with the detent 30, which in turn will release star-wheel 21 and permit rotation of the various pinions and therefore actuation of the striker 20 caused by detent 30 riding over the star-wheel 21.

Assuming that the user has also set the auxiliary or cartridge firing mechanism as previously described, the continued rotation of the main spring arbor and therefore arbor 63 will cause the latter to rotate into engagement with the depending pawl 64, forcing the pawl in counter-clockwise direction, in Figure 6, until it engages with the 100

lower end of lever 62, and oscillates the latter sufficiently to raise the plunger or trigger 54 where its notch 61 is freed from the wall portion 56 and allows the sudden forward movement of the plunger through the action of spring 57. The pawl 64 is then free to drop into its depending position shown in full lines in Figure 6.

The construction shown I believe to be a simple adaptation of my invention as applied to a jewel or cash box, although adapted for other uses; the invention having been described in terms employed merely as terms of description and not as terms of limitation as structural modifications are possible and may be made without, however, departing from the spirit of my invention.

What I claim is:

1. Alarm mechanism, comprising an energized alarm element, spring controlled means adapted to control the alarm element, a vertically movable plunger provided with a laterally swinging lower end, means whereby said end is normally held against lateral movement, a spring controlled lever intermediate of said spring controlled means and said plunger whereby said spring controlled means is moved into alarm releasing position when said plunger moves downward, and a gravity actuated member pivotally mounted beneath the yielding lower end of said plunger, whereby the latter is held against downward movement while the gravity actuated member is in alignment therewith.

2. Alarm mechanism, comprising an energized alarm element, a spring controlled member for controlling said alarm element, a spring controlled plunger for controlling said member, a pivoted lever normally tending to move said plunger out of controlling relation with the spring controlled member, a vertically movable plunger operatively connected with said lever so as to hold the latter out of operative relation with said first plunger, said vertically movable plunger being provided with a laterally yieldable attenuated lower end, means whereby said vertically movable plunger may be held against downward movement, and a gravity controlled member oscillatably mounted beneath said vertically movable plunger and provided with an attenuated portion adapted to receive the attenuated lower end of said vertically movable plunger to hold said plunger against downward movement.

3. Alarm mechanism, comprising an energized alarm element, a spring-controlled plunger adapted to control the release of said alarm element, a spring pressed lever adapted to control said plunger, a vertically movable plunger having controlling relation with said lever, said last plunger having an attenuated lower end and normally tending to move downwardly, a guide

for said last plunger, means secured to said plunger and adapted to engage with said guide when in one position and thereby hold said vertically movable plunger against movement, and an oscillatably mounted weighted member provided with an attenuated upper portion on which the attenuated lower end of the vertically movable plunger normally rests when the weighted member is in alignment with the vertical axis of said plunger and said means has been moved to plunger-releasing position.

4. Alarm mechanism, comprising an energized alarm element, a spring controlled plunger adapted to control the release of said alarm element, a pivoted lever adapted to control said plunger, a vertically movable plunger having controlling relation with said lever, a slotted casing in which said last plunger reciprocates, means secured to said plunger, adapted to move through the slot of said casing, said means being adapted to be moved laterally out of register with said slot, to hold the plunger against downward movement, said last plunger being provided with a yieldable lower end adapted to move laterally when said plunger moves toward the lower end of said casing, and an oscillatably mounted weighted member on which the lower end of said plunger normally rests when the weighted member is in alignment with the vertical axis of said plunger.

5. Alarm mechanism of the character described, comprising an alarm element, means whereby said element is actuated, a vertically movable plunger, means whereby said plunger may be held against downward movement, a spring-controlled plunger adapted to control said first mentioned means, a spring pressed lever intermediate of said plungers and controlled by said first plunger whereby the second plunger is actuated against the action of its spring when the first plunger moves downwardly, and gravity-controlled means having a fixed pivoted relation relative to the first mentioned plunger whereby downward movement of said plunger is prevented when said gravity controlled means is in vertical alignment with said plunger.

6. In alarm mechanism of the character described, comprising a spring-controlled alarm element provided with an arbor actuated by the spring, a gear mounted on said arbor to rotate therewith, a pinion meshing with said gear, a second gear operatively connected with said pinion to rotate therewith, a second pinion with which the last mentioned gear meshes, a striker-actuating star-wheel operatively secured to said last mentioned pinion, a spring-controlled member adapted to hold said star-wheel with said gears and pinions against rotation, a spring-controlled pivoted lever adapted to move said member out of

holding relation with the star-wheel, a vertically movable plunger operatively connected with said lever, means whereby said plunger may be held against movement, and 5 gravity-actuated means pivotally mounted against vertical movement but adapted to swing laterally, whereby the vertically movable plunger will be held against movement when the gravity-controlled actuated means 10 is in vertical position.

7. In alarm mechanism of the character described, an alarm element, a vertically movable plunger, a housing in which the plunger reciprocates, means whereby the 15 plunger may be held against vertical movement, the lower end of said housing being provided with an extension or bracket disposed beneath the path of the plunger, gravity-controlled means pivotally mounted on 20 said bracket to swing laterally, said plunger and means being provided with contacting points, a spring-controlled member normally holding said alarm element against alarm-sounding operation, a spring-controlled lever 25 operatively connected with said plunger, adapted to force said last mentioned member out of holding relation with the alarm element when said plunger moves downwardly upon movement of the gravity-controlled 30 means out of alignment with said plunger.

8. In alarm mechanism, an alarm element, a vertically movable plunger provided with a laterally movable contact-forming portion, a housing in which said plunger is slidably 35 mounted, a pivot-providing bracket immovably arranged beneath the path of said plunger, a gravity-controlled pendant pivoted on said bracket to swing laterally and provided with an upwardly disposed contact- 40 forming portion normally adapted to contact with the contact-forming portion of the plunger to prevent downward movement of the latter, a spring-controlled plunger where-

by the alarm element is normally held against actuation, a spring-controlled lever, 45 pivoted intermediate of its ends, with one end having operative connection with said vertically movable plunger, while the other end is adapted to shift said second mentioned plunger out of alarm element arresting position when said pendant swings out of holding relation with the vertically movable plunger, and means secured to the upper end of the vertically movable plunger adapted to engage with said housing to 50 hold the plunger against downward movement.

9. In alarm mechanism of the character described, an alarm element, a vertically movable plunger provided with a laterally 55 yieldable contact-forming point, a slotted housing in which the plunger is slidable, a latch member swiveled on said plunger and adapted to move in a slot of the housing when moved out of latching position and 60 into alignment with said slot, a bracket secured beneath said housing, a gravity actuated member loosely mounted on said bracket and provided with a contact-forming point on which the contact-forming point of 65 the plunger is adapted to rest when in alignment, a spring-controlled plunger normally adapted to arrest the alarm element, and a spring-controlled lever pivoted intermediate of its ends with one end disposed 70 through a slot in said housing and operatively connected with the vertically movable plunger, while the other end has sliding relation with the end of the spring-controlled plunger and is adapted to force said plunger 75 out of arresting position when the first mentioned plunger moves downwardly.
